US0D1038935S

(12) **United States Design Patent** (10) Patent No.: **US D1,038,935 S**
(45) Date of Patent: ** Aug. 13, 2024

(54) **ELECTRONIC DEVICE**

(71) Applicant: **Amazon Technologies, Inc.**, Seattle, WA (US)

(72) Inventors: **Wen-Yo Lu**, Pasadena, CA (US); **Mei-Hsuan Chen**, Taipei (TW); **Michael Robert Harris**, Phoenixville, PA (US); **Hung-Yen Hsieh**, Taoyuan (TW); **Gerald Richard Iannelli**, Marlton, NJ (US); **James Siminoff**, Pacific Palisades, CA (US); **Mark D. Siminoff**, Mountain View, CA (US); **Anita Thomas**, Collegeville, PA (US); **Timothy Wellener**, Phoenixville, PA (US)

(73) Assignee: **Amazon Technologies, Inc.**, Seattle, WA (US)

(**) Term: **15 Years**

(21) Appl. No.: **29/798,142**

(22) Filed: **Jul. 6, 2021**

(51) LOC (14) Cl. **14-02**

(52) U.S. Cl.

CLAIM

The ornamental design for an electronic device, as shown and described.

DESCRIPTION

FIG. 1 is a top, front, right-side perspective view of an electronic device;

FIG. 2 is a bottom, back, left-side perspective view thereof;

FIG. 3 is a front view thereof;

FIG. 4 is a back view thereof;

FIG. 5 is a left-side view thereof;

FIG. 6 is a right-side view thereof;

FIG. 7 is a top view thereof; and,

FIG. 8 is a bottom view thereof.

The dashed broken lines depict portions of the electronic device that form no part of the claimed design.

(Continued)

The dot-dashed broken lines represent boundaries of the claimed electronic device and form no part of the claimed design.

1 Claim, 8 Drawing Sheets
